US0D1107574S

(12) **United States Design Patent** (10) **Patent No.:** **US D1,107,574 S**
(45) **Date of Patent:** **** Dec. 30, 2025**

(54) **GAS DETECTION DEVICE**

(71) Applicant: **Welmade Technology Corporation**,
Phoenix, AZ (US)

(72) Inventor: **Yi-Nan Kuo**, Hsinchu (TW)

(73) Assignee: **Welmade Technology Corporation**,
Phoenix, AZ (US)

(**) Term: **15 Years**

(21) Appl. No.: **29/854,556**

(22) Filed: **Sep. 26, 2022**

(51) LOC (15) Cl. **10-05**

(52) U.S. Cl.

USPC **D10/106.2**; D10/81

(58) **Field of Classification Search**

USPC D10/81, 106.1–106.4, 104.1; D24/232;
D23/200, 318
CPC . G08B 21/12; G01N 1/24; G01N 1/26; G01N
1/2273; G01N 2001/002; C12M 41/48;
C12M 41/34; C12M 41/00

(57) **CLAIM**

The ornamental design for a gas detection device as shown and described.

DESCRIPTION

FIG. 1 is a top, front, and right perspective view of a gas detection device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of the encircled portion 8 shown in FIG. 1.

The broken lines in the drawings illustrate portions of the gas detection device which form no part of the claimed design.

1 Claim, 7 Drawing Sheets
